US00D849864S

(12) **United States Design Patent** (10) **Patent No.:** **US D849,864 S**
Hsiang (45) **Date of Patent:** **** May 28, 2019**

(54) **TRAMPOLINE SUPPORT PIPE**

(71) Applicant: **Crowntec (Jiang Xi) Sports Technology Co. Ltd.**, Jiujiang, Jiangxi Province (CN)

(72) Inventor: **Hua-Lu Hsiang**, Taoyuan (TW)

(73) Assignee: **CROWNTEC (JIANG XI) SPORTS TECHNOLOGY CO., LTD.**, Jiujiang, Jiangxi Province (CN)

(**) Term: **15 Years**

(21) Appl. No.: **29/630,065**

(22) Filed: **Dec. 19, 2017**

(51) LOC (11) Cl. **21-02**

(52) U.S. Cl.

USPC **D21/797**

(57) **CLAIM**

The ornamental design for a trampoline support pipe, as shown and described.

DESCRIPTION

FIG. 1 is a perspective view of a trampoline support pipe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view thereof.

The broken lines shown in the figures are for the purpose of illustrating portions of the trampoline support pipe, which form no part of the claimed design.

1 Claim, 8 Drawing Sheets
